(57) **CLAIM**

The ornamental design for an identifying tag for a microcentrifuge tube, as shown and described.

DESCRIPTION

FIG. 1 is a front perspective view of an identifying tag for a microcentrifuge tube showing my new design;

FIG. 2 is a front elevational view of FIG. 1; the undisclosed rear elevational view being a mirror image thereof, aside from the unclaimed indicia appearing thereon;

FIG. 3 is a side edge elevational view of FIG. 2, the undisclosed opposite side being a mirror image thereof;

FIG. 4 is a top edge view of FIG. 2;

FIG. 5 is a bottom edge view of FIG. 2; and,

FIG. 6 is another perspective view, in a reduced scale, displaying the claimed invention affixed to an exemplary microcentrifuge tube in accordance with my design.

In the drawings, the broken lines illustrate environment and form no part of the claimed design.
